UNITED STATES PATENT OFFICE.

JAMES S. CRUMP, OF WILLIAMSBURG, MISSOURI.

IMPROVEMENT IN HARVESTER-RAKES.

Specification forming part of Letters Patent No. 71,994, dated December 10, 1867.

To all whom it may concern:

Be it known that I, JAMES S. CRUMP, of Williamsburg, county of Calloway, State of Missouri, have invented a new and useful Improvement in Dropper-Platforms for Harvesters; and I do hereby declare that the following is a full, clear, and exact description of the construction and operation of the same, reference being had to the annexed drawing, making a part of this specification, in which—

Figure 1 is a side elevation of my improved dropper, with the inner shoe and a portion of the inner standard or support broken away, for the purpose of better illustrating some of the parts; and Fig. 2 is a detached view of the eccentric arm by means of which the dropper is operated.

My invention consists in a novel arrangement of means for operating the dropper-platform; in the employment of peculiarly-constructed adjustable "cant" or deflecting boards in combination with the dropper; and in the arrangement of means for adjusting the dropper-platform to adapt it to the character of the grain in which it is operated, as hereinafter explained.

To enable others to understand and use my invention, I will proceed to describe the same with reference to the drawing.

A represents the finger-beam of a harvester, attached at its outer end to a divider or dividing-board or runner, B, of any suitable or usual construction, and at its inner end to a similar shoe or runner, and to the main frame of the machine either directly or through the inner shoe, and by means of a hinge or rigid connection, as preferred.

C is a cant or deflecting board, attached to the outer shoe or dividing-board by means of bolts or screws, (represented at a,) and made adjustable thereon, to admit of varying its relation to the finger-bar and dropper by means of a series of holes, a¹ a¹, through any one of which the holding-screw may be passed for securing it to the divider. A similar deflecting-board is secured to the inner shoe, or to other suitable support, at the inner end of the finger-beam, and made adjustable in a similar manner.

D¹ are standards or uprights secured to the dividing-board and inner shoe or frames.

These uprights may be arranged in a vertical position at or near the finger-bar, as shown; or they may be placed some distance in rear of said bar in such position as to insure their being out of the way of the falling grain, and inclined forward in such manner as to afford a support or bearing at a suitable height, either directly or through horizontal arm D², for the rock-shaft E, as shown in Fig. 1.

F are pendent arms, bolted or otherwise secured to the rock-shaft E, to the lower end of which are secured, by means of removable pins, bolts, or screws, the adjustable inclined arms G, so arranged as to support the platform H, secured thereto in a suitable position to receive the grain as it is cut, and from which it is discharged upon the ground, in a manner hereinafter explained.

I (see Fig. 2) is a curved arm, provided with the sleeve I¹, which fits upon one end of the rock-shaft, and is adjusted and held in the desired relation thereto (see Fig. 1) by means of set-screw i.

J is a flat spring, riveted at its lower end to the arm I, and at its upper end bearing against and working upon a stud or arm, D³, secured to the rear end of arm D².

K is another spring, wound or coiled upon a drum, L, attached to standard D¹. Said spring is provided at its free end with a loop, which may be made to fit over the free end of the arm or rod I, and may be used instead of spring J, or may be made supplementary thereto, for the purpose of increasing the tension upon said arm, as the nature of the work may require.

M is a lever, provided with or rigidly connected to an upright, N, which is pivoted in an arm attached to the inner standard, as shown at N', Fig. 1. The rear end of lever M is provided with a grooved friction-roller, O, so arranged as to work against or in contact with the curved rod I; and the forward end of said lever is provided with the treadle P, which is intended, in practice, to be so arranged as to be in convenient position to be operated by the foot of the driver in his seat on the machine.

The operation is as follows: The machine being advanced over the ground, and motion imparted to the cutters in the usual manner, the grain, as it is cut, is deposited upon the

platform H. The cant-boards C, which overlap its ends when in position to receive the grain, as shown by the drawings, tend to deflect the grain inward toward the center of said platform, thereby bringing it into a compact mass until sufficient quantity is deposited to form a gavel, when the driver, in his seat on the machine, by pressing with his foot upon treadle P, causes the lever M to vibrate upon its fulcrum N', thereby swinging the rear end of said lever backward and upward, carrying with it the curved eccentric arm I, and causing the rock-shaft E to roll in its bearings, when the platform, suspended therefrom, is swung backward and upward into position shown by red lines in the drawing, thereby giving to the platform such an inclination as will cause the grain to slide off and be deposited in a compact gavel upon the ground. The foot of the attendant is now raised or removed from the treadle P, when the weight of the platform, assisted by the springs J K, one or both, causes the platform immediately to return into position to receive the grain as it is cut, until another gavel is formed, when the operation is repeated. The lever M may be so arranged as to be operated by hand, or automatically, if preferred.

The cant-boards C, as above explained, are made adjustable relative to the finger-bar, and may be set forward or back, according to the character of the grain, whether long or short; and the platform is also made adjustable upon the pendent arms F or bodily upon the supporting-standards D D¹, by means of perfora-

tions and set-screw or pins d d¹, for a similar purpose. These cant-boards are cut away on their under rear surfaces, in the manner shown by the drawing, to receive and cover the ends of the platform, and when adjusted or set backward carry the platform back with them, and thus adapt the platform to receive long grain, and vice versa. The platform is set up and down for a like purpose, and also for the purpose of causing it to work in proper relation to the cant-boards when thus adjusted.

Having now described my invention, what I claim, and desire to secure by Letters Patent, is—

1. The curved eccentric arm I, applied to the rock-shaft E, and operated in the manner and for the purpose described.
2. The swinging lever M, or its equivalent, in combination with the curved eccentric arm, for operating the platform, as described.
3. The arrangement of one or more springs in combination with the curved eccentric arm I, for the purpose set forth.
4. The manner of adjusting the height of the swinging platform upon the supporting arms and uprights.
5. The adjustable cant or deflecting boards C, in combination with the swinging platform, as described.

In testimony whereof, witness my hand this 12th day of October, 1867.

JAMES S. CRUMP.
